CLAIM

The ornamental design for a slider mobile telephone, as shown and described.

DESCRIPTION

FIG. 1 is a front side perspective view of the slider mobile telephone in a closed configuration showing my design;

FIG. 2 is a front view thereof;

FIG. 3 is side view thereof;

FIG. 4 is a rear view thereof;

FIG. 5 is an opposing side view of the view shown in FIG. 3;

FIG. 6 is a bottom end view thereof;

FIG. 7 is a top end view thereof;

FIG. 8 is a front side perspective view thereof illustrating the slider mobile telephone of FIG. 1 in an open configuration;

FIG. 9 is a front view thereof;

FIG. 10 is a side view thereof;

FIG. 11 is a rear view thereof; and,

FIG. 12 is an opposing side view of the view shown in FIG. 10.

The broken lines immediately adjacent the shaded areas represent the bounds of the claimed design while all other broken lines are directed to environment and are for illustrative purposes only; the broken lines form no part of the claimed design.
